VACUUM CLEANER

George W. Allen and Lena B. Allen, Boston,
Mass., assignors to B. F. Sturtevant Company,
Hyde Park, Mass., a corporation of Massachusetts

Application August 27, 1929, Serial No. 388,729

16 Claims.

(Cl. 15—155)

The present invention relates to vacuum cleaners and more particularly to suction nozzles for the same.

One of the objects of the present invention is 5 to devise a construction of suction nozzle which shall be particularly effective in the picking up of stringy material such as threads, hair, etc.

Another object is to provide a suction nozzle 10 whereby pile fabrics, and particularly those of the deep pile type, will be thoroughly and easily cleaned.

Another object is to produce a suction nozzle 15 which will offer a minimum of resistance to movement over the surface to be cleaned, irrespective of the character of such surface.

With these objects in view the present invention consists of the parts and combinations of parts hereinafter described and more particularly defined in the appended claims.

20 In the common construction of suction nozzle having a plain, elongated, narrow slot, difficulty has been experienced in picking up stringy material such as thread, string, hair, etc., and this difficulty is increased as the depth of the pile increases. Various attempts have been made to 25 improve the operation of nozzles with regard to such materials. In some instances revolving or stationary brushes have been located in the mouth of the nozzle; blades or surfaces, both having plain and also having serrated edges, have been placed within or adjacent the nozzle mouth. Other devices have been tried, but none have 30 proved wholly satisfactory. Where brushes were employed, whether stationary or revolving, the stringy material tended to collect thereon, requiring frequent cleaning. Blades were only partially effective in picking up the threads and were liable to damage the fabric being cleaned.

35 The present invention avoids all liability of damage to the fabric, at the same time insuring the picking up of all such material and the delivery of the same into the dust receptacle by directing a stream of air in a direction approaching parallelism with the surface to be cleaned and at a point adjacent the mouth of the nozzle, whereby the pile will be bent over sidewise and the thread or other stringy material blown off the same and carried into the mouth of the nozzle.

40 Preferably two streams of air will be employed, one at the front of the nozzle to bend the fibres 45 backwardly towards the nozzle mouth, and a similar stream at the rear of the nozzle bending the fibres forwardly towards such mouth. Thus, as 50 the nozzle is passed over the surface to be cleaned

in either direction, the fibres will be bent first in one direction and then in the other by the air currents, and any stringy material which may have become lodged or entangled on either side thereof will be swept off and through the mouth 5 of the nozzle and into the dust receptacle.

Such bending of the fibres of the pile not only facilitates the dislodging of the stringy material but also opens up the fabric so that the dirt and dust may be drawn from the depths thereof. Furthermore, due to the forcible bending of the fibres or pile, first in one direction and then the other, any dirt or dust lodged upon the fibres will be shaken or thrown off and carried away in the air stream.

55 In the accompanying drawing which illustrates what is now considered the preferred embodiment of the present invention, Fig. 1 shows in side elevation an electric vacuum cleaner of a common type provided with a nozzle constructed in accordance with the present invention; Fig. 2 is a bottom plan view of the nozzle on an enlarged scale, with parts broken away to show the interior construction; Fig. 3 is a transverse sectional view, on a still larger scale, on line 3—3 20 of Fig. 2, but with the nozzle in normal, operating position, instead of bottom side up as shown in Fig. 2; Fig. 4 is a front elevation of one end of the nozzle on the same scale as Fig. 3, with the protecting rubber band cut away; and Fig. 5 is a 25 view similar to Fig. 3, showing a band in position to close the auxiliary air inlet.

The cleaner illustrated in Fig. 1 is of the conventional type, comprising the usual fan casing 5 with fan 6 therein, electric motor 7, supporting 30 wheels 9, dust bag connection 10, handle 11, and inlet passage 13, with the nozzle indicated generally at 15. In operation the front end of the cleaner is supported by the nozzle, the under face 35 of which is in direct contact with the surface to be cleaned.

The nozzle is constructed as shown in Figs. 2, 3, and 4, and comprises a hollow downwardly curved, laterally flaring body, having a long, narrow slot 17 extending across the bottom thereof between the horizontal end partitions 19. Close to the nozzle mouth and extending along the front and rear thereof are the front and rear air inlets 21 and 23, respectively, through which air is supplied to the nap or pile of the fabric to be cleaned 40 in approximately opposite directions parallel to the surface of the fabric.

In the specific construction illustrated in the drawing, the nozzle is made in two parts, one part comprising the downwardly curving and lat- 45

erally extending portion with top and depending wall around the margin or periphery thereof, all cast integrally with the suction passage 13 and the fan casing 5, and the other part consisting of a detachable bottom portion in which are formed the slot or mouth 17 and the air inlets 21 and 23. In Fig. 3 is shown the cast top portion 25 with the depending wall 27. Secured against the bottom face of this wall is the bottom portion 10 of the nozzle, indicated generally at 29, which comprises the substantially flat front and rear bottom faces 31 spaced apart to provide for the slot 17 and inlets 21, 23, with the upturned front and rear walls 33 terminating short of the 15 walls 27 of the main portion of the nozzle to form air entrance portions 35 and 37 in the front and rear of the nozzle.

Inclined partitions 39, extending from the bottom faces of the side walls 27 of the upper portions 10 of the nozzle, with their lower ends spaced from the bottom faces 31 to form the air inlets 21 and 23, and from each other to form the slot or mouth 17, terminate slightly above the plane of the lower surface of the bottom faces and 25 direct the air entering the ports 35 and 37 through the inlets 21 and 23 and onto the fabric adjacent the slot 17. These partitions at their upper ends have short, horizontal portions 41, and at intervals are provided with upturned lugs or 30 ears 43 received in recesses 45 in the depending wall 27 and secured therein by means of the screws 47. Six of these attaching lugs are shown in Fig. 2 whereby the detachable lower portion 29 is firmly mounted upon the lower face of the 35 upper portion of the nozzle, the outer margin of the bottom face of the wall 27 and the inner margin of the horizontal walls or faces 41 fitting closely together.

A round rubber band 49, to protect furniture 40 or other articles from being scratched or marked if the cleaner nozzle should accidentally be brought into contact therewith, is positioned on the outer faces of the wall 27, being held in place in stretched condition between the overhanging 45 top or lip 51 on the upper portion and the horizontal face 41 on the bottom portion of the nozzle. This rubber band, through its close contact with the upper and lower portions of the nozzle, also serves to prevent any leakage between these two 50 parts, if through faulty mechanical construction they fit poorly.

In order to support or strengthen the inclined partitions 39 and also to distribute the suction more uniformly across the width of the nozzle, 55 vertical partitions 53 are inserted between the inclined partitions 39 and the bottom and side walls 31 and 33. In the construction shown in Fig. 2, eight of these partitions are shown, four in front of the inlet slot 17 and four to the rear.

60 To facilitate cleaning close to a wall or an article of furniture rising vertically from the floor, the horizontal end partitions 19 are formed with a semi-circular groove 55 in their lower faces, constituting extensions, as it were, of the inlet slot 17. By operating the cleaner parallel to a side wall with one end of the nozzle close to such wall, this groove 55 as it passes over the surface to be cleaned will permit the passage of air to the inlet nozzle, and with such air will be 65 carried the dust and dirt from the surface passed over.

The cleaner illustrated in the drawing and embodying the present invention is operated in the same manner as the ordinary cleaner of this 75 general type, being propelled over the floor or

surface to be cleaned by the operator and the suction or current of air induced by the motor-driven fan picking up and carrying the dust and dirt to the usual dust receptacle. A portion of the air for this current or stream is supplied by 5 the air inlets adjacent the nozzle slot, the air so supplied being delivered onto the surface to be cleaned in a direction approximating the horizontal. All stringy material such as threads, strings, hair, etc., as well as ordinary dust and 10 dirt, are thoroughly and completely picked up and removed. That portion of the air stream supplied from directly beneath the slot draws the dirt and dust from the deeper portions of the 15 material to be cleaned.

Not only is the nozzle constructed in accordance with the present invention particularly effective in picking up stringy material from the surface to be cleaned, but owing to the flat bottom faces of the nozzle which contact with such 20 surface, and to the length of such faces measured in the direction of travel of the cleaner, the latter will be propelled with a minimum of effort on the part of the operator, the nozzle sliding 25 freely with slight resistance irrespective of the character of such surface.

Where the air inlets at the front and rear of the slot 17 are not required or desired, as for example where there are no threads or stringy material to be picked up, or maximum suction is 30 needed for extra deep cleaning or for some other reason, the air ports 35 and 37 may be closed in any convenient manner as for example by means of the rubber band as shown at 51 in Fig. 5.

While the present invention has been illustrated 35 and described in connection with a particular construction of the parts, it is not limited thereto but may be employed in many other forms and arrangements.

Nor is the present invention limited to a construction of nozzle in which a lower part is 40 detachably secured upon the main body of the nozzle except where so specifically defined in the claims.

Having thus described the present invention, 45 what is claimed is:

1. A vacuum cleaner nozzle comprising a hollow body portion having a bottom with a flat work-engaging surface and an unobstructed suction mouth therein, the total width of the flat 50 work-engaging surface in the direction of travel of the nozzle exceeding the width of the nozzle slot, thereby to facilitate movement of the nozzle over the surface to be cleaned, the hollow body portion also being provided with air passages having air inlets and air outlets which are adjacent the suction mouth at the front and the rear thereof of one wall of each of the air passages being substantially parallel to the surface to be cleaned 55 whereby air is delivered to said surface adjacent the suction mouth.

2. A vacuum cleaner nozzle comprising a hollow body portion having a bottom provided with a long, narrow, unobstructed suction mouth and a pair of air passages of fixed dimensions, one 60 to the front and the other to the rear of the mouth, the passages being symmetrically arranged with respect to the mouth, a wall of each passage being substantially horizontal adjacent the mouth to deliver air at the same inclination 65 over the surface to be cleaned adjacent the mouth in approximately opposite directions.

3. A vacuum cleaner nozzle comprising a hollow flaring body portion, a suction mouth portion, and means for securing the portions to- 70

- gether, the suction mouth portion having a bottom provided with a suction mouth, side walls rising from the bottom and terminating short of the top of said portion to form air inlets, and 5 inclined partitions extending from the top of the mouth portion toward the suction mouth and terminating adjacent thereto to form with bottom air outlets and to direct air from the air inlets onto the surface to be cleaned adjacent 10 the suction mouth.
4. The combination with a vacuum cleaner nozzle comprising a hollow body portion, front and rear walls, and a bottom, the bottom being provided with an unobstructed suction mouth 15 and with an air passage having an air outlet adjacent thereto, and one of the walls having an air inlet for admitting air to the passage, of an elastic band for covering and closing the air inlet.
- 20 5. A vacuum cleaner nozzle comprising a long, narrow flaring body portion, a suction mouth portion having a long, narrow suction mouth in its bottom and auxiliary air inlet ports in its sides, means for detachably securing the suction 25 mouth portion to the body portion, an elastic band for covering the joint between said portions to prevent leakage of air therethrough, the body portion and the mouth portion being provided with band engaging shoulders to retain 30 the band in position, and the mouth portion being adapted to receive and retain a band in position to close the ports.
6. A vacuum cleaner nozzle comprising a hollow, flaring body portion, a suction mouth portion 35 provided with a suction mouth and with an auxiliary air passage and detachably secured to the body portion, and an elastic bumper band held by its own elasticity in engagement with the body and the suction mouth portions for preventing air leakage through the joint between such portions.
7. The combination with a vacuum cleaner nozzle comprising a hollow, flaring body portion provided at its bottom with a long, narrow suction mouth and with an air passage having a 45 normally open air inlet and an air outlet which is adjacent the suction mouth, one wall of the passage being substantially parallel to the surface to be cleaned whereby air is delivered to such surface in a direction approximately parallel to the same, and a bumper band for covering the air inlet at the will of the operator.
8. A vacuum cleaner nozzle comprising a hollow body portion having a long narrow suction mouth, a suction chamber immediately above the suction mouth, and an auxiliary air chamber having an air outlet adjacent to the suction mouth, the body having auxiliary air inlet means 55 extending substantially throughout the length thereof to direct air into the auxiliary chamber, the auxiliary chamber having a substantially flat bottom to direct air substantially horizontally over the work and into the suction mouth at right angles thereto.
- 60 9. The combination with a vacuum cleaner nozzle comprising a hollow body portion and a suction mouth portion detachably secured thereto, of an elastic bumper band, the adjacent portions of the body portion and the suction mouth portion cooperating to form a supporting groove to receive and retain the bumper band by its own elasticity, whereby the band may be removed while maintaining the mouth portion secured to 65 the body portion.
10. A vacuum cleaner nozzle comprising a body having a bottom with a flat work-engaging surface and an unobstructed mouth therein, the body being provided with an air passage having an inlet open to the atmosphere, and with an air 5 outlet adjacent the suction mouth to deliver air onto the surface to be cleaned, one wall of the air passage being substantially parallel to said surface.
11. A vacuum cleaner nozzle comprising a hollow body portion having a mouth and a suction chamber directly above the mouth, and an auxiliary air chamber having a substantially horizontal bottom plate to engage the work adjacent to the mouth and spaced from the mouth to provide an air outlet, the chamber having an auxiliary air inlet above the bottom plate, and a partition leading downwardly from above the auxiliary air inlet and inclined toward the suction mouth, the partition and horizontal bottom plate 20 serving to direct air from the auxiliary air inlet through the air outlet and substantially horizontally across the work adjacent to the suction mouth.
- 25 12. A vacuum cleaner nozzle comprising a hollow, flaring body portion and a detachable mouth portion, said body portion having a bottom face and a laterally extending overhanging wall spaced above said face, and the mouth portion engaging the bottom face of the body portion and being of greater width than said body portion 30 face to form with the overhanging wall a groove for retaining an elastic band.
- 35 13. A vacuum cleaner nozzle comprising a hollow, flaring body portion and a detachable mouth portion having flat bottom faces to engage the work, the faces being spaced apart to form a long narrow mouth, and a partition extending downwardly from the body portion with its bottom edge slightly above the bottom of the mouth 40 portion and between the inner margins thereof to form an air outlet at one side of the partition between a bottom face of the mouth portion and the bottom edge of said partition, and a suction mouth on the opposite side of said partition, the nozzle having an open auxiliary air inlet above the mouth portion to supply air to 45 said outlet.
- 50 14. A vacuum cleaner nozzle comprising a hollow, flaring body portion and a detachable mouth portion having flat bottom faces to engage the work, the faces being spaced apart to form a long narrow mouth, a partition extending downwardly from the body portion to form on one side with the body portion a suction chamber 55 and on the other side an auxiliary air chamber partially closed at its bottom by a bottom face of the detachable mouth portion, the bottom edges of the partition being slightly above the bottom of the mouth portion and between the inner margins of the mouth to divide the mouth into a suction mouth for the suction chamber and an air outlet for the auxiliary air chamber, said chamber being provided with an auxiliary air inlet above the mouth portion.
- 60 15. The combination with a vacuum cleaner nozzle comprising an integrally cast hollow, downwardly curved laterally flaring body portion and a detachable mouth portion having a long, narrow suction mouth formed therein and substantially flat bottom faces adjacent said mouth to the front and rear thereof, the front edge of the front face and the rear edge of the rear face being provided with upwardly turned extensions.
- 70 75

of an elastic bumper band held by its own elasticity in engagement with and positioned by the upturned extensions and removable therefrom while maintaining the mouth portion secured to the body portion.

16. A vacuum cleaner nozzle comprising a hollow body portion having a long narrow suction mouth and a suction chamber directly above the mouth, and an auxiliary air chamber having a substantially horizontal bottom plate to engage

the work adjacent to the mouth, the plate being cut away adjacent the mouth portion to form an air outlet, the chamber having an auxiliary air inlet above the bottom plate, and a partition leading from above the auxiliary inlet and down to substantially the top of the bottom plate to direct air substantially horizontally across the work adjacent the suction mouth.
